CLAIM

The ornamental design for a menstrual cup with detachable ribbon, as shown and described.

DESCRIPTION

FIG. 1 is a front perspective view of one embodiment of a menstrual cup with detachable ribbon;

FIG. 2 is a left side view of the menstrual cup with detachable ribbon of FIG. 1;

FIG. 3 is a right side view of the menstrual cup with detachable ribbon of FIG. 1;

FIG. 4 is a bottom perspective view of the menstrual cup with detachable ribbon of FIG. 1;

FIG. 5 is a top perspective view of the menstrual cup with detachable ribbon of FIG. 1;

FIG. 6 is a front view of the menstrual cup of FIG. 1, shown without the detachable ribbon for ease of illustration;

FIG. 7 is a left side view of the menstrual cup of FIG. 1, shown without the detachable ribbon for ease of illustration;

FIG. 8 is a right side view of the menstrual cup of FIG. 1, shown without the detachable ribbon for ease of illustration;

FIG. 9 is a bottom perspective view of the menstrual cup of FIG. 1, shown without the detachable ribbon for ease of illustration; and,

FIG. 10 is a top perspective view of the menstrual cup of FIG. 1, shown without the detachable ribbon for ease of illustration.
